UNITED STATES PATENT OFFICE.

MARTIN CHRISTENSEN, OF RACINE, WISCONSIN, ASSIGNOR TO CHRISTENSEN MACHINE COMPANY, OF RACINE, WISCONSIN, A CORPORATION OF WISCONSIN.

CONVEYER FOR BOOK-STITCHING MACHINES.

1,348,849.

Specification of Letters Patent. Patented Aug. 10, 1920.

Application filed May 28, 1917. Serial No. 171,442.

To all whom it may concern:

Be it known that I, MARTIN CHRISTENSEN, a citizen of the United States, and resident of Racine, in the county of Racine and State 5 of Wisconsin, have invented new and useful Improvements in Conveyers for Book-Stitching Machines, of which the following is a description, reference being had to the accompanying drawings, which are a part of 10 this specification.

The invention relates to conveyers for book-stitching machines.

In stitching machines one type of conveyer for carrying the signatures consists 15 of a movable saddle upon which the signatures are placed astride of the same and are moved along with the saddle and their rear edges abut against pins or pusher members secured to the saddle. It frequently happens 20 in practice that owing to the speed at which the conveyer is run or to the sizes of the sheets carried by it that different spacings of the pins on the conveyer becomes necessary and of course it is essential 25 that the adjustment be made in the quickest and easiest manner possible. It is therefore the object of this invention to provide the conveyers with a quickly detachable pin or pusher member which may be secured to the 30 conveyer in any desired adjustment to accommodate for the requirements of the work.

The invention is further designed to provide a construction in which the pusher 35 members may be snapped into place on the conveyer and quickly removed therefrom.

The invention is further designed to provide a construction in which the pusher members are secured to the conveyer by 40 resilient means which may be either the resiliency of the metal forming the member or an auxiliary spring.

The invention further consists in the several features hereinafter set forth.

45 In the drawings:

Figure 1 is a side view of the device embodying the invention showing it applied to one form of movable saddle conveyer;

Fig. 2 is a section taken on the line 2—2 50 of Fig. 1;

Fig. 3 is a modified form of device embodying the invention, showing it applied to another form of movable saddle conveyer;

Fig. 4 is a section taken on the line 4—4 of Fig. 3;

55

Fig. 5 is another form of device embodying the invention showing it applied to another form of conveyer;

Fig. 6 is a section taken on the lines 6—6 of Fig. 5;

60

Fig. 7 is another form of device embodying the invention;

Fig. 8 is a section taken on the line 8—8 of Fig. 7.

In Figs. 1 and 2, I have shown the preferred embodiment of the invention which consists of a pusher member 9, formed by a metal bar bent upon itself to form overlapped curved ends 10 and 11 which spread apart owing to the natural elasticity of the 65 metal which may be of common bar stock. This form of device may be used in connection with any suitable form of movable saddle conveyer and in the drawings I have shown a portion of a conveyer consisting of 70 a plurality of inverted V-shaped members 12 hingedly connected together and running in a guide 13.

The particular form of saddle conveyer is immaterial so further detailed description 80 of the conveyer is considered unnecessary.

The pusher member 9 is detachably secured to the conveyer by inserting the curved end 10 through aligned rectangular holes 14 in opposite sides of one of the members 12 so 85 that the ends 10 and 11 project outwardly and upwardly from the sides of the conveyer to form abutments for the rear edges of a group of signatures placed upon the conveyer and one side of the member is provided with a notch 15 which receives one edge of the member 12 at the openings 14 nearest the open portions of the bar and said member is held to the member by the resiliency or elasticity of the parts which tend to 90 spread apart and hold them against the sides of the holes 14 and in addition the notch 15 locks the member 9 against lengthwise movement while the rectangular holes 14 with the member 9 shaped to fit said holes prevents 100 any relative movement of said member 9 with respect to the member 12. It will be noted from Fig. 1 that each of the members 12 is provided with the holes 14 so that the position of the pusher members 9 may be 105 changed along the length of the conveyer.

The device may be readily removed by pressing the spread apart portions of the end 11 together to disengage the notch 15 from the member 12 and then removing it 5 while to replace it it is only necessary to push it through the holes 14 and allow it to be snapped into locking engagement with the member 12.

In Figs. 3 and 4 I have shown a form 10 of device embodying the invention consisting of a yielding member 16 having outwardly and upwardly extending connected together arms 17, depending side portions 18 and inturned flanges 19, said device being 15 adapted to snap over the members 12' forming the conveyer, which are somewhat similar to those forming the conveyer shown in Figs. 1 and 2. This form of device is locked to the member to which it is connected by 20 inwardly extending projections 20 engaging in holes or depressions 21 in the sides of the members 12' which coöperate with the flanges 19 to lock or hold the device in position as shown in Fig. 4. It will be noted 25 that this form of device may also be used in connection with the conveyer shown in Figs. 1 and 2.

In Figs. 5 and 6 I have shown another 30 form of device embodying the invention consisting of a yielding member 22 shaped to conform to the contour of the member 23 forming part of the conveyer and having an upstanding finger 24. This device is adapted to be snapped down over any of 35 the members 23 and to be locked thereto by inwardly extending sets of projections 25 engaging in holes or depressions 26 in the sides of the members 23. For further detailed description of the conveyer shown 40 in these figures reference may be had to my Patent No. 1,140,734, dated May 25, 1915.

In Figs. 7 and 8 I have shown another 45 form of device embodying the invention consisting of an angled member 27 provided with a barrel 28 having a bore 28' in which a square locking rod 29 is slidably mounted. This rod has a square head 30 which may be inserted in the large square openings 31 in any one of the conveyer 50 members 12 or any other suitable conveyer member after which the device is moved laterally so that the square rod 29 engages in the small rectangular opening 32 leading from the opening 31. A spring 33 is 55 interposed between the top of the rod 29 and the barrel 28 and by pressing inwardly against the spring 33, inserting the head of the rod 29 through the opening 31 and then moving the rod into the slot 32 and 60 releasing the spring the pusher member will be held to the conveyer member 12' by the clamping action of the head 30 and member 27 thereby locking the parts together through a snap connection, the

squared contacting parts preventing lateral 65 movement of the member 27 with respect to the member to which it is connected.

It will thus be apparent that the pusher devices may be readily attached to any one of the conveyer members desired by a quick 70 detachable interlocking connection between the pushers and the conveyer members to accommodate for the requirements of the work in hand.

I am aware that the details of construction herein shown and described are subject to some modification and change, and I desire it to be understood that such changes as come within the scope of the appended claims I deem to be within the spirit of my 80 invention.

What I claim as my invention is:

1. The combination, with one of the members of a saddle conveyer having a plurality of apertures therein, of a yielding 85 pusher member having a portion thereof insertible through the apertures in the saddle member to project outwardly from the sides thereof, said pusher member yieldingly clampingly engaging said saddle 90 member adjacent said apertures and held thereby against movement.

2. The combination, with one of the members of a saddle conveyer having a plurality of alined apertures therein, of a bar 95 bent upon itself to form a pusher member having spread apart portions at one end, said bar being insertible within the alined apertures in the saddle member and having arms extending outwardly beyond said 100 saddle member, and a detachable interlockable connection between the spread apart portions and the side of the apertures adjacent thereto.

3. The combination, with one of the members of a saddle conveyer having alined apertures therein, of a bar bent upon itself to form a pusher member having spread 110 apart yieldable portions at one end, said bar being insertible within the alined apertures and having arms extending outwardly and upwardly from the saddle member, and having a notch in one of said spread apart portions adapted to be yieldingly held against the side of the aperture adjacent 115 thereto.

4. In a device of the class described, the combination with an endless conveyer provided with a plurality of spaced seats, of pusher members engageable in said seats 120 and having substantially rigid and interchangeable connection with the seats but being capable of ready detachment therefrom.

In testimony whereof, I affix my signature. 125

MARTIN CHRISTENSEN.
